UNITED STATES PATENT OFFICE

2,523,805

MECHANICAL GOLF BALL PROJECTOR

Samuel A. Anthony, Tucson, Ariz.

Application August 23, 1946, Serial No. 692,475

5 Claims. (Cl. 124—16)

1

This invention relates to improvements in mechanical golfing devices for projecting golf balls.

An object of the invention is to provide an improved mechanical golfing device for shooting a golf ball when playing golf rather than using regulation golf sticks.

Another object of the invention is to provide an improved wheeled mechanical golfing device which will include a compressible spring mechanism for projecting a ball to simulate driving when playing golf.

A further object of the invention is to provide an improved spring operated golf ball projecting device which may be variably tensioned to shoot a golf ball varying distances from one place to another, as, for example, from a driving tee to a golf course green.

Another object of the invention is to provide an improved, mechanically compressed spring mechanism for projecting a golf ball, said mechanism being provided with an improved cocking trigger device whereby the same may be released upon the operation thereof.

Another object of the invention is to provide an improved mechanical golf ball driving device which will be highly efficient in operation, and relatively inexpensive to manufacture and produce.

Other objects will appear as the description proceeds.

In the accompanying drawings which form a part of this application,

Figure 1 is a side elevation of the improved mechanical golf device;

Figure 2 is a plan view of the improved mechanical golf device;

Figure 3 is a longitudinal sectional view taken on the line 3—3 of Figure 2;

Figure 4 is a sectional view taken on the line 4—4 of Figure 3;

Figure 5 is an end elevational view looking from the right of Figure 3;

Figure 6 is a transverse sectional view taken on the line 6—6 of Figure 3;

Figure 7 is a rear view of the improved mechanical golf device; and

Figure 8 is a sectional view taken on the line 8—8 of Figure 1.

Like characters of reference are used throughout the following specification and the accompanying drawings to designate corresponding parts.

In carrying out the invention, there is provided a pair of supporting wheels 1 and 2, the same being suitably mounted in the forks 3 and 4, which are open at their upper ends and are adapted to support the inverted U-shape frame member 5 with its oppositely disposed depending arms 6 and 7 telescopically received within the open ends of the said forks 3 and 4, and held in

2

the desired vertically adjusted positions by means of the bolts and wing nuts 8 and 9. The transversely extending bracing arm 10 is connected between the opposite side arms 6 and 7 and is arranged in spaced position below the said upper arm 5 and extends parallel therewith.

The housing 11 is supported upon the transversely extending arms 5 and 10, and supports the elevating pinion 12 upon a transversely mounted shaft therein, which, in turn, supports the crank handle 13 on its outer extremity. The vertically extending rack bar 14 is disposed in a vertical slot formed through the housing 11 and supports the spring projecting gun mechanism upon the cross pivot pins 15 at the lower end of said rack bar 14.

The barrel 16 of the device is supported by means of the spaced bands or yokes 17 and 18 which are secured about the same, and extend upwardly therefrom, and are connected by means of the connecting arm 19 disposed above said barrel 16 and in spaced relation thereto. A pulley 20 is mounted transversely at the forward end of said connecting arm between the same and said barrel 16, while the rear pulley 21 is supported at the rear end of the said connecting arm 19 for purposes hereinafter described.

The barrel 16 is tubular in shape, and is internally threaded at its rear end, as at 22, and is adapted to receive the externally threaded rear closure member 23, as clearly shown in Figure 3 of the drawings. A cylindrical hard wood guide 24 is mounted in the forward end of the barrel 16, and is supported therein by the screws 25 extending through said barrel and into said guide. The opposite ends of the hard wood guide 24 are flared so that the head member 26 on the forward end of the golf ball projecting rod 27 will slide within the hollow bore through said guide.

The rear end of the rod 27 is threaded to receive the bearing disk 28, which is threaded thereon. A second bearing disk 29 is loosely mounted upon the rod 27 forwardly of the bearing disk 28, and serves with said bearing disk 28 to limit the position of the cushioning spring 30 disposed about said rod 27, to take up the impact of the rod as it is projected forwardly at a high rate of speed to drive the golf ball 31 which will be supported upon the rubber tee 32 on the arm 33 which is pivotally supported at the forward end of the arm 34 whose rear end is pivoted at 35 to the lug 36 on the lower portion of said barrel 16.

A trigger bracket 38 is provided which slides over the surface of the barrel 16. The trigger bracket 38 is provided with the forwardly extending, oppositely disposed arms 39, in which the vertical shafts 40 are mounted for rotary movement. The rearwardly extending links 41 are secured to the vertical shafts 40 and are mounted in slots in the transversely adjustable trigger

members or keepers 42, which normally extend inwardly through the slots 46 in the barrel 16 directly in front of the rear bearing disk 28 so that movement to the rear being had by the trigger member 42 will cause the bearing disk 28 to move rearwardly also to compress the powerful coil spring 43 disposed between the rear surface of the bearing disk 28 and the rear closure member 23. The inwardly directed trigger arms 44 will be secured to the upper ends of the vertical shaft 40 and will be tied together by means of the link 45, in such a manner that when the arms 44 are moved rearwardly, the trigger keepers or members 42 will move outwardly from the sides of the barrel 16 to release the bearing disk 28 on the rear end of the projecting rod 27, thereby permitting the same to be projected at a high rate of speed to the forward end of the barrel, at which time the cushioning spring 30 will act as a shock absorber to take care of the shock incident to the forward movement of said rod.

The reel 47 will be provided with a hand operating crank 48, and said reel will be supported above the rear end of the barrel 16 by means of the U-shape clip 49 secured to said barrel.

The inverted V-shape casing 50 will be supported by the clamping member 51 about the barrel 16 slightly forward of the reel 47, and will support the pulley 52 in its upper end, and will be provided with the aperture 53 through which the trigger actuating cable 54 will extend. Opposed pulleys 55 and 56 will be supported respectively on the front and rear of the casing 50 to support the said trigger actuating cable 54 in a manner later to be described. The trigger lever 57 will be pivoted at 58 to the casing 50 and will be provided with the arm 59, which will be connected by the link or arm 60 to the bell crank lever 61 pivoted at 62 in the casing 50. A rod 63 will be secured to the lower arm of the bell crank lever 61 and will support the sheave 64 which will be disposed below the trigger cable 54 and in contact therewith, whereby, when said trigger lever 57 is pulled rearwardly, the associated linkage will cause the sheave 64 to move upwardly to pull backward upon the trigger actuating cable 54, which movement will be transmitted through the cable 54 which is connected to the link 45 so as to move the trigger arms 44 rearwardly, thereby moving the trigger keepers or members 42 outwardly to release the golf ball projecting rod. A coil spring 65 will be disposed in the trigger actuating cable line 54 to allow a small amount of expansion in the otherwise taut trigger actuating cable.

The setting cable 66 will be secured to the eyes 67 in the rear of the trigger bracket member 38, and will be secured to the reel so that rotation of the operating crank 48 will pull backwards upon the trigger bracket member 38 until it reaches the desired position to project the ball the necessary distance. If desired, the trigger keeper or bracket member 38 may be pulled all the way back until it reaches the rear end of the oppositely disposed slots 46 through the sides of the barrel 16.

The trigger cable 54 will be secured to the forward end of the turnbuckle 69 and will then be connected to the link 45, and from thence it will be connected to the coil spring 65 and about the forward pulley 28 and rearwardly under the pulley 21 and through the aperture 53 to extend over the pulley 52 and will be wound two turns about the reel 47 and from thence under the pulley 56,

over the sheave 64 and under the pulley 55 and back to the rear end of the turnbuckle 69.

The handle arm 70 will be supported upon the rear end of the barrel 16, and will be bent upwardly and rearwardly therefrom, terminating in the hand-grip portion 71, whereby said device may be pulled from place to place, or may be sighted when getting ready to project the golf ball.

10 The rearwardly extending telescoping brace rods 72 will be connected at their forward ends to the frame of the device, and will be connected at their rear ends to the ears 74 secured to the opposite sides of said barrel 16. Suitable locking 15 wing nuts 75 will extend through the brace rods 72 to clamp the smaller brace rod 73 telescopically received within the same, in the desired adjusted position.

From the foregoing description, it will be seen 20 that the improved mechanical golfing device may be readily transported from place to place by means of the handle arm 70 and hand-grip portion 71. After actuating the trigger 57 to remove 25 the keepers 42 from the path of bearing disk 28 and project the ball, the operator manually slides the bracket 38 over the gun barrel to a position ahead of the bearing disk 28, all the time maintaining a pressure on trigger 57 to prevent keepers 42 from catching on the coils of the expanded 30 projecting spring. It will also be seen that the barrel may be elevated vertically for projecting the ball a further distance, and that the device may be turned laterally from side to side on its supporting wheels 1 and 2.

35 From the foregoing description, it will be seen that there has been provided a highly efficient form of mechanical golfing device which may be operated by one man to project or shoot a golf ball a great distance, and that the distance may 40 be gauged by means of varying the compression upon the spring 43.

While the preferred embodiment of the instant 45 invention has been illustrated and described, it will be understood that it is not intended to limit the scope of the invention thereto, as many minor changes in detail of construction may be resorted to without departure from the spirit of the invention.

Having thus described my invention, what I 50 claim as new and desire to secure by Letters Patent of the United States is:

1. In combination with a mechanical golfing device including a wheeled frame, a barrel supported thereon, a projecting spring in said barrel, 55 and a golf ball supporting tee mounted at the forward end thereof, longitudinal slots in said barrel, a trigger bracket slidable on said barrel, a disk slidable in said barrel, a golf ball projecting rod carried by said disk, movable keepers slidable in said slots adapted to engage said disk, means secured to said bracket engaging said keepers, and means secured to said bracket and operatively connected to said keeper-engaging means for laterally moving said keepers out of engagement with said disk to actuate the device.

2. In combination with a mechanical golfing device including a wheeled frame, a barrel supported thereon, a projecting spring in said barrel, and a golf ball supporting tee mounted at the forward end thereof, longitudinal slots in said barrel, a trigger bracket slidable on said barrel, a disk slidable in said barrel, a golf ball projecting rod carried by said disk, movable keepers slidable in said slots and adapted to engage said disk, 70 link means pivotally secured in said bracket and

engaging said keepers, trigger arms operatively connected to said link means, and means operatively connected to said trigger arms for actuating said trigger arms and thereby pivoting said link means to release said disk.

3. In combination with a mechanical golfing device including a wheeled frame, a barrel supported thereon, a projecting spring in said barrel, and a golf ball supporting tee mounted at the forward end thereof, longitudinal slots in said barrel, a trigger bracket slideable on said barrel, a disk slideable in said barrel, a golf ball projecting rod carried by said disk, movable keepers slideable in said slots and adapted to engage said disk, vertical shafts rotatably mounted in said bracket, link means secured to said shafts and engaging said keepers, trigger arms connected to said shafts, means joining said trigger arms, a reel mounted on said device and means rotatable on said reel and secured to said joining means to actuate said trigger arms and thereby pivot said link means to release said disk.

4. The combination of claim 3 wherein said reel includes a drum, means mounting said drum on said barrel, cable means secured to said bracket and rotatable on said drum, separate cable means secured to said trigger arms and wound about said drum, and means to operate said drum to retract said bracket and said disk.

5. The combination of claim 4 wherein said last-named cable means includes a coil spring and a plurality of rollers mounted on said barrel and around which said last-named cable means travels.
